United States Patent Office

Des. 197,713
Patented Mar. 17, 1964

197,713

CHAIR

Richard W. Bedser, 212 Henry Clay Road, Ashland, Va.

Filed Mar. 18, 1963, Ser. No. 74,021

Term of patent 14 years

(Cl. D15—1)

Fig. 1.

Fig. 2.

Fig. 4.

Fig. 3.

FIGURE 1 is a front elevational view of a chair showing my design;

FIGURE 2 is a side elevational view;

FIGURE 3 is a top plan view; and

FIGURE 4 is a front perspective view thereof.

The rear of the backrest support is plain and unornamented.

I claim:

The ornamental design for a chair, substantially as shown and described.
